CLAIM

The ornamental design for a three-wheeled vehicle, substantially as shown.

DESCRIPTION

FIG. 1 is a top plan view of a three-wheeled vehicle showing my design;

FIG. 2 is a side elevational view thereof, the opposite side being a mirror image of the side shown herein except for the omission of the passenger door;

FIG. 3 is a bottom plan view thereof;

FIG. 4 is a front elevational view thereof; and

FIG. 5 is a rear elevational view thereof.

FIG. 4

FIG. 5
